UNITED STATES PATENT OFFICE.

VANCE E. TAYLOR, OF ST. LOUIS, MISSOURI.

INTERLOCKING TILE.

1,415,906.

Specification of Letters Patent. Patented May 16, 1922.

Application filed July 14, 1919. Serial No. 310,799.

To all whom it may concern:

Be it known that I, VANCE E. TAYLOR, a citizen of the United States of America, a resident of the city of St. Louis, in the 5 State of Missouri, have invented certain new and useful Improvements in Interlocking Tiles, of which the following is a full, clear, and exact description, reference being had to the accompanying drawings, forming a 10 part of this specification.

My invention relates to tiles intended more particularly for use in building sewers and other conduits, and has for its object the production of a single ring tile sewer structure built up of segmental tile sections in such manner as to provide leak-proof end joints between the tile sections, this object being attained partially through the medium of tongue and groove sealed connections between the ends of the tile sections, and partially through the provision of cavities in the tile sections into which mortar may become embedded to form seals, aside from that formed between the tongue and groove 25 portions of the sections.

Fig. I is a perspective of a fragment of one of my tile sections showing the tongue at an end thereof.

Fig. II is a fragment of one of the tile 30 sections showing a groove in its end suitable for the reception of the tongue shown in Fig. I.

Fig. III is a longitudinal section of portions of two of the tile sections joined to 35 each other.

In the accompanying drawings, A and B 40 designate tile sections adapted to be placed in interlocking relation with each other at their ends. The tile section A is provided with an end tongue 1, and the tile section B is provided with an end groove 3 adapted to receive the tongue of the section A. The opposite end of each section is similar to the end of the other section shown in the 45 drawings.

When the blocks A and B are fitted together end to end, the tongue 1 of one section occupies a position between the two webs 5 and 6 adjoining the groove 3 in the 50 next tile section, as seen in Fig. III. The tongue 1 is carried by a web 7 spaced from webs 8 and 9, thereby providing cavities 10 and 11 extending into the section at its end from which the tongue projects. Beyond the

inner end of the groove 3 in companion section 55 is a web 12 spaced from the webs 5 and 6, thereby providing cavities 13 and 14 at opposite sides of the web 12.

When mortar is applied to the ends of the tile sections A and B, said ends and the 60 tongue 1 are coated with mortar and the mortar enters into the groove 3 in the section B and also enters into the cavities 10 and 11 in the section A. Then when the sections are brought together end to end, and 65 the tongue of one section is forced into the end groove in the other section, mortar lying in the groove will be partially forced therefrom into the cavities 13 and 14, at opposite sides of the web 12 extending to the base of 70 said groove. A mortar seal joint is therefore furnished between the opposing ends of the tile sections at opposite sides of the tongue 1 and at the end of said tongue, the mortar seal extending also into the cavities 10 and 75 11 in the section A, back of the end of said section and into the cavities 13 and 14 beyond the base of the groove 3 and at opposite sides of the web 12. Such a mortar joint forms an effective seal at the junction 80 of the tile sections to preclude the passage of mortar therethrough, and the mortar is securely held in the joint. However, as an additional sealing provision, I preferably form in the tile sections cavities 15 and 16, 85 which extend inwardly from their ends and coincide with each other when the sections are joined end to end. These cavities 15 and 16 also receive mortar when it is applied to the ends of the tile sections, so that they 90 serve as supplemental baffles for the exclusion of moisture that might pass directly along the end faces of the tile sections in the absence of the sealing mortar extending into said cavities.

To eliminate the possibility of mortar being scraped from the surfaces of the tongue 1 and the walls of the end groove 3, when tile sections are fitted together, I form ribs 2 upon the faces of the tongue 1 and 100 ribs 4 upon the walls of the groove 3, which, by coinciding with each other, serve to prevent the tongue from scraping against the walls of the groove when introduced into the groove. As a consequence the tongue will 105 always be so positioned in the groove of the adjoining block as to provide a body of mortar at both sides of the tongue, even in

the event of the tile sections being imperfectly fitted to each other.

I claim:

An interlocking tile structure comprising
5 tile sections, one of which is provided with
an end groove and the other with an end
tongue entering into said end groove, each
of said tile sections being provided with a
plurality of cavities which extend longitudi-
10 nally through said tile sections, the cavi-
ties of one tile section being adapted to reg-
ister with the cavities of another tile section
when said tile sections are placed in juxtapo-

position, one of the cavities in the tile sec-
tion having a tongue being located imme-
diately above said tongue and another of
said cavities being located immediately be-
low said tongue, and a mortar seal connect-
ing said tile sections together, said mortar
seal being interposed between the edges of 20
adjacent tile sections and extending into and
entirely filling the end portions of said cavi-
ties adjacent to said tongue and groove.

In testimony that I claim the foregoing I
hereunto affix my signature.

VANCE E. TAYLOR.
